(57) **CLAIM**

The ornamental design for a scissors handle, as shown and described.

DESCRIPTION

FIG. 1 is a perspective view of one embodiment of the inventor's scissors handle;
FIG. 2 is a perspective view from the opposite side of the scissors shown in FIG. 1;
FIG. 3 is a top view of the scissors handle;
FIG. 4 is a side view of the scissors handle;
FIG. 5 is an end view taken from one end of the scissors handle;
FIG. 6 is a bottom view of the scissors handle;
FIG. 7 is a side view of the scissors handle taken from the side opposite from that of FIG. 4;
FIG. 8 is an end view of the scissors handle opposite from that of FIG. 5;
FIG. 9 is a top view of a first modified form of the scissors handle;
FIG. 10 is a side view of a first modified form of the scissors handle;
FIG. 11 is an end view of said first modified form of the scissors handle;
FIG. 12 is a bottom view of said first modified form of the scissors handle;
FIG. 13 is a side view from the side opposite from that of FIG. 10 of said first modified form of the scissors handle;
FIG. 14 is an end view opposite from that of FIG. 11 of said first modified form of the scissors handle;
FIG. 15 is a top view of a second modified form of the scissors handle;
FIG. 16 is a side view of said second modified form of the scissors handle;
FIG. 17 is an end view of said second modified form of the scissors handle;
FIG. 18 is a bottom view of said second modified form of the scissors handle;
FIG. 19 is a side view opposite from that of FIG. 16 of said second modified form of the scissors handle; and,
FIG. 20 is an end view opposite from that of FIG. 17 of said second modified form of the scissors handle.
The broken lines shown on the drawings are for illustrative purposes only and form no part of the claimed design.
